DESIGN FOR A GAME-BOARD

Andrew B. Lail, Washington, D. C., assignor of one-fourth to Edward W. Ritchie, Washington, D. C.

Application May 3, 1937, Serial No. 69,137

Term of patent 14 years

To all whom it may concern:

Be it known that I, Andrew B. Lail, a citizen of the United States, residing at 3900 14th Street, N. W., in the city of Washington, District of Columbia, have invented a new, original, and ornamental Design for a Game-Board, of which the following is a specification, reference being had to the accompanying drawing, forming part thereof, in which:

The design is characterized by the subdued showing of the several pictorial representations of governmental agencies in the symmetrical arrangement shown.

I claim:

The ornamental design for a game-board, substantially as shown and described.

ANDREW B. LAIL.
